9 Claims. (Cl. 242—66)

1

This invention relates to a machine for winding web material, such as paper, to produce a roll of the desired hardness irrespective of the weight of the roll.

Specifically, the invention deals with a drum winder adapted to produce very soft rolls of paper, such as creped tissue paper, without being influenced by the weight of the roll being wound.

Drum winders characteristically produce wound rolls of web material which increase in hardness as the weight of the roll increases. Prior attempts to counterbalance the weight of the roll being wound have not been successful, because the roll lifting force must be applied to the projecting end portions of the shaft on which the roll is being wound and, since this shaft must be of relatively small diameter in comparison with its length, deflection of the shaft and the roll has occurred. As a result, the central portion of the roll was not benefited, and uneven winding was obtained.

According to this invention, however, a drum winder is equipped with fluid pressure operated jacks acting on the ends of the winder shaft to relieve some of the load of the roll being wound from the winder drums, and deflection of the shaft is so controlled that the roll being wound will have equal pressure contact with the winder drums along its entire length. To accomplish this result, the winder shaft need not be increased in diameter over heretofore used shafts, or made heavier than the prior used shafts. Actually, the winder shaft arrangement used in the machine of the present invention can be made hollow and lighter in weight than heretofore used shafts of similar length. The winder shaft assembly, in accordance with this invention, includes a through shaft or axle carrying a shell in spaced concentric relation therearound and supported thereon only through deflectable carriers between the shaft and shell and positioned at localized points inwardly from the ends of the shell and outwardly from the axial center of the shaft. A preferred location for the supporting means between the shaft and shell is inwardly from the ends of the shell a distance of approximately one-fifth of the total shell length. Only two localized support areas are used and they, of course, will then be separated a distance equivalent to three-fifths of the shell length. The shell is thereby supported so that the deflection at the ends of the shell will be equal to the deflection of the shell at a point mid-way between the supporting ends of the shaft. The anti-deflection shaft arrangement obviates any neces-

2

sity for crowning against deflection, and, since crowning is highly objectionable in winder shafts because a crowned shaft cannot be pulled out of a roll without damaging the roll, it is clear that the anti-deflection assembly fills a long felt want.

It is, then, an object of this invention to provide a drum winder with a counterbalanced winder shaft that will maintain equal pressure between the roll being wound and the winding mechanism throughout the entire length of the roll.

A further object of the invention is to provide a drum winder adapted to produce a very soft roll of uniform softness throughout its entire length.

Another object of the invention is to provide an under drum type paper winder with fluid pressure actuated jacks relieving the weight of the roll being wound on the under drum by acting on the winder shaft without in any way deflecting the roll along its length.

A specific object of the invention is to provide a twin under drum paper winder with winder shaft lifting jacks to relieve the load of the roll being wound on the winder drums by lifting the ends of a winder shaft which will not deflect to permit uneven loading of the roll being wound on the winder drums.

Another and specific object of the invention is to provide a twin drum paper winder with an air cylinder counterbalance and a chain safety lift acting on the ends of a winder shaft to relieve the load of the roll being wound on the winder drums without deflecting the roll along its length.

Other and further objects of this invention will be apparent to those skilled in the art from the following detailed description of the annexed sheets of drawings which, by way of a preferred embodiment only, illustrate one winder machine according to this invention.

On the drawings:

Figure 1 is a broken front elevational view, with parts in vertical cross section, of a winder machine according to this invention.

Fig. 2 is an end elevational view of the machine of Figure 1.

Figure 3 is a broken vertical cross-sectional view, with parts in elevation, of an anti-deflection winder shaft used on the machine of Figures 1 and 2.

Figure 4 is a view similar to Figure 3 on an enlarged scale and with parts omitted and with other parts in elevation, illustrating the positions of the parts when the shaft is unloaded.

Figure 5 is a view similar to Figure 4 but illus-

trating the positions of the parts when the shaft is heavily loaded.

Figure 6 is an enlarged transverse cross-sectional view taken along the line VI-VI of Figure 3.

As shown on the drawings:

As shown in Figures 1 and 2, the winder machine 10 of this invention includes side frames 11, 11 carrying bearing supports for rotatably mounting a pair of spaced horizontally aligned winder drums 12 coaxing to define a winder nip 13 therebetween. Upstanding end frame portions 11a, 11a carry vertical tracks 14, 14 in which are slidably mounted carriages 15, 15 each having a split bearing clamp 16 at the lower end thereof projecting into alignment with the winder nip 13 beyond the ends of the winder drums 12. The carriages 15 have bosses 15a on the rear faces thereof slidably receiving mounting pins 17.

The pin has heads 17a at the opposite ends thereof and compression springs 18 are disposed around the pin between these heads and the adjacent ends of the boss 15a. Each head 17a is pivotally connected at its outer end with the end of a sprocket chain 19 that is trained around a bottom sprocket 20 rotatably mounted on the frame portion 11a and a top sprocket 21 secured on a cross shaft 22 which is rotatably mounted on the end frame portions 11a. The shaft 22 is rotated by means of a sprocket 23 on one end thereof driven by a chain 24 which, in turn, is actuated from a sprocket 25 on a hand wheel-actuated shaft 26 carried by the end frame. The shaft 26 carries a ratchet 27 engaged by a pawl 28. The pawl 28 can be disengaged from the ratchet by raising a lever 29. The lever 29 is conveniently actuated by the end of a rod 30 which is raised and lowered from a foot pedal 31, pivoted on the bottom of the frame. The hand wheel-actuated shaft 26 is operative to rotate the cross shaft 22 in a direction for causing the sprocket 21 to drive the chains 19 for raising the carriages 15 in their tracks. The pawl 28 is effective to hold the shaft 22 against rotation in the opposite direction but can be released from the ratchet so as to permit this opposite rotation. The springs 18 serve to form resilient supports for the carriages 15 on the sprocket chains 19. The bearing clamps 16 carried by the carriages therefore have spring mountings on the lifting chains.

The frames 11 also carry vertical jack cylinders 32 with pistons 33 slidable therein and actuating piston rods 34 which project out of the open tops thereof. The upper ends of the piston rods are pivotally connected to the bearing clamps 16 on the carriages 15. Fluid such as air under pressure is admitted into the bottom ends of the jack cylinders 32 through pipes 35 fed from a single source 36 so that pressure in each jack will be equal. The fluid forces the pistons 33 upwardly in the cylinders to raise the piston rods 34 and thereby raise the bearing clamps 16.

A paper web W is fed to the nip 13 around the under side of one of the winder drums 12. As shown in Figure 2, the web W is directed into the winder machine 10 around the top side of a roll 37 and over an adjustable guide bar 38 which laps the web around the under side of the first winder drum 12.

An ejector roll 39 for pushing a wound paper roll out of the winding nip 13 is carried on gear segments 40 at the ends of the first under drum 12 and is swingable over the roll 12. Pinion gears 41 in engagement with the arcuate gear

segments 40 are effective to swing the roll 39 through the nip 13 to eject the wound roll.

The split bearing clamps 16 surround winder shaft bearings 42 on the ends of a winder shaft 43. As best shown in Figure 3, the bearings 42 have segmental spherical cap receiving portions 42a which are adapted to tilt in the clamps to provide a self-aligning bearing connection. The bearings 42 are freely rotatable about stub shafts 44 on anti-friction bearings (not shown). These stub shafts 44 are anchored into the ends of a tubular axle 45 by means of locking pins 46. The stub shafts project into the ends of the axle 45 for a relatively short distance only. A cylindrical shell 47 surrounds the tubular axle 45 in spaced concentric relation and is mounted on the axle by a pair of rubber mountings 48 each composed of a plurality of rubber rings of circular cross section in side by side relationship. Six rubber rings are illustrated as constituting each mounting 48.

As best shown in Figures 4 and 5, the axle 45 has reduced diameter portions 45a equivalent in width to the length of the mountings 48 and affording end or abutment shoulders 45b for the end rings of each mounting. These shoulders 45b are effective to hold the rings in side by side relationship.

Metal retainer rings 49 snugly fit inside of the shell 47 and are positioned in the shell to abut the inner rubber ring of the mountings 48. These retainer rings 49 are welded in position to the shell 47 at the time of making the assembly, so that the retainers will abut the mountings. As shown in Figure 4, spot welds 50 in holes in the shell 47 can be used to anchor the abutment rings 49 in place.

The shell has an end ring or collar 51 shrunk on one end thereof and also anchored by pins 52. A spacer sleeve 53 is mounted on the shell in abutting relation to the inner end of the end ring 51. A second spacer sleeve 53 is provided on the other end of the shaft and is abutted by an end collar 54 which is internally threaded and receives, in threaded relation therein, a second end collar 55. A split locking collar or retainer ring 56 abuts the outer end of the collar 55 to define an abutment shoulder therefor and is seated in a groove 57 formed in the shell 47. The collar 56 has pivoted together sections on a pivot pin 58 and is adapted to be readily swung open and moved out of the groove 57. When the collar 56 is locked in the groove 57, the end collar 55 can be adjusted in the collar 54 to adjustably space the second spacer sleeve 53 from the first spacer sleeve 53 at the other end of the shell and thereby accurately control the dimension between the spacers 53 in accordance with the width of the web W to be wound on the roll. A cardboard winder tube (not shown) receives the paper web therearound and is clamped on the shaft between the sleeves 53.

The bearing clamps 16 are split so as to be quickly engaged on the bearing portions 42a of the shaft bearings 42. Each bearing clamp 16 includes a fixed lower half portion 16a on the carriage 15 and a swingable top half portion 16b which is pivoted on a pin 16c carried by the carriage 15. A keeper 16d on the free end of the swingable bearing portion 16b engages a latch or locking dog 59 which is pivoted on a pin 60 carried by the lower half 16a of the clamp. A spring 70 urges the latch against the keeper to lock the two halves 16a and 16b together. An operating handle 71 on the lower end of the latch,

however, is adapted to depress the spring for releasing the latch from the keeper 16d. A handle 72 is provided on the swingable section 16b to raise and lower the section for opening and closing the clamp.

In operation of the winder machine 10 of this invention, the paper W is fed under the first under drum 12 as explained above and is directed upwardly into the nip 13. A winder tube is clamped between the spacer sleeves 13 as explained above. The winder shaft 43 has the end bearings 42 thereof mounted in the bearing clamps 16 and the carriages 15 are lowered sufficiently so that the winding tube on the shell 47 of the winder shaft will rest in the nip 13 in engagement with both drums 12. In order to lower the winder shaft, fluid in the cylinders 32 is exhausted and the foot pedal 31 is depressed to permit the hand wheel to be swung in a direction for lowering the carriages 15. The leading end of the paper web is then threaded around the winding tube. The leading end of the paper is then clamped on the shell 47 and the drums are driven to rotate the shaft and tube so that a roll builds up on the shaft in contact with the under drums 12.

As the roll increases in diameter, the winder shaft raises in the nip 13 and the weight of the roll increases, thereby increasing the pressure relationship between the paper and the winder drums. In order to relieve the weight of the roll from the winder drums so as to maintain a desired pressure relationship between the paper being wound and the winder drums, air or other fluid under pressure is fed from the supply pipe 36 through the pipes 37 to the cylinders 32 under pistons 33 for causing the piston rods 34 to raise the bearing clamps 16.

As the load of the roll being wound is transferred from the winder drums to the fluid pressure jacks, the tubular axle portion 45 of the anti-deflection winder shaft 43 will deflect as diagrammatically shown in Figure 5. This deflection will be appreciable as the weight of the roll increases and as more and more of the roll weight is borne by the jacks acting through the bearings at the ends of the shaft. However, the shell 47 on the shaft, being supported inwardly from the ends of the tubular axle 45, will only deflect in such a way as to prevent any appreciable variation in pressure between the roll being wound and the winder drums along the length of the roll.

Thus, as shown in Figure 5, the end portions A of the shell are cantilever supported from the supports 48 and tend to deflect downwardly at their free ends under heavy load. The central portion B of the shell 47 also tends to deflect downwardly under load, but this portion is supported at its ends by the supports 48 and is in the nature of an end supported beam, the downward deflection of which opposes the downward deflection of the cantilever ends or beams A. As a result, deflections at A and B tend to neutralize each other and a substantially straight cylindrical shape is maintained irrespective of the catenary-like deflection of the supporting axle. The rubber rings forming the supports 48 will deform through interparticle flow of the rubber to permit relative deflection between the axle and shell without galling any of the metal parts by permitting metal to metal contact therebetween.

In order to substantially close the open ends of the shell 47, end plates or caps 73 (Figure 3) are provided on the stub axles 44 in closely spaced relation from the ends of the shell. These caps

can carry deformable seal rings 74 in opposed relation to the ends of the shell to prevent any metal to metal contact between the caps and shell.

The fluid pressure admitted to the lifting cylinders 32 can be controlled so as to cause the jacks to relieve any desired proportion of the weight of the roll being wound from the winder drums so that a constant winding pressure is maintained to produce a uniformly wound roll. As the winder shaft rises up from the nip 13, the bearing clamps will be lifted therewith and the carriages 15 will rise in their tracks, causing the chains 19 to rotate the shaft 22 in a counter-clockwise direction. This shaft, in turn, drives the chain 24 to rotate the ratchet 27 in a counter-clockwise direction. The pawl 28 will not interfere with counter-clockwise rotation of the ratchet and the carriages 15 can therefore rise in their tracks. If desired, however, some spring compression can be maintained on the supporting springs for the carriages by operation of the hand wheel shaft 26. In the event of failure of pressure in the lifting jacks, the pawl will prevent the carriages from dropping, so that the roll will be supported. It should be noted that the pawl 28 will prevent clockwise rotation of the shaft 22.

When the winding operation is completed, the bearing clamps 16 are opened up by releasing the latches 59 and the gear segments 40 are swung to move the discharge roller 39 over the first winder drum 12 and against the roll, thereby pushing the roll out of the nip 13 and out of the lower halves 16a of the bearing caps.

From the above descriptions it will therefore be understood that this invention provides a winder machine which will relieve any desired portion of the weight of a roll being wound from the winder drums and will maintain a uniform weight distribution throughout the length of the roll, irrespective of the weight of the roll. The invention provides a novel anti-deflection winder shaft including a deflectable through shaft or axle and a paper roll supporting shell carried thereby at localized points so positioned as to neutralize deflection.

It will be understood that modifications and variations may be effected without departing from the scope of the novel concepts of the present invention.

I claim as my invention:

1. A drum winder for web material comprising a pair of under winder drums defining a winding nip, vertical tracks at the ends of one drum, carriages slideable in said tracks, bearing clamps carried by said carriages adjacent the ends of said nip, upper and lower sprockets at opposite ends of each track, a lifting chain for each carriage trained around the adjacent upper and lower sprockets, means for selectively locking the upper sprockets against rotation in a direction permitting lowering of the carriages, a fluid pressure jack adjacent each end of the nip, a piston rod projecting from each jack acting on the adjacent bearing clamp to raise and lower the clamps relative to the nip, a winder shaft having bearings on the ends thereof receivable in said bearing clamps, a cylindrical shell enveloping said shaft between the bearings, resiliently deformable means connecting the shell and shaft at localized areas inwardly from the ends of the shell and outwardly from the central portion of the shaft to form the sole support for the shell, a fixed end collar on one end of the

shell, a spacer sleeve on said shell abutting said end collar, an internally threaded collar slidable on the other end of the shell, an externally threaded collar threaded into said internally threaded collar, said shell having a peripheral groove near the end thereof carrying the threaded collar, a split retainer ring selectively locked in said groove for receiving the externally threaded collar thereagainst, whereby the internally threaded collar is adjustable toward and away from the collar at the other end of the shaft, a second spacer sleeve thrusting against said internally threaded collar, and said sleeves adapted to clamp therebetween a winder tube for a roll of paper, whereby a web wound on said shaft can have selected pressure engagement with said winder drums along its entire width by partially supporting the weight of the roll and shaft on said jacks.

2. A winder machine adapted for producing a wound roll of a controlled uniform degree of hardness irrespective of the weight thereof which comprises a pair of under winder drums defining a winding nip, vertical tracks on said machine adjacent the ends of the winder drums, split bearing clamps slidably supported in said tracks, fluid pressure operated jacks engaging said clamps for raising and lowering the clamps in the tracks, a winder shaft extending along the length of said winding nip and having end portions projecting through the bearing clamps, a shell enveloping said shaft along the length thereof lying within said nip, and resilient deflectable means inwardly from the ends of the shell and outwardly from the central portion of the axle, whereby a roll wound on said shell will not deflect in response to deflection of the shaft upon carrying the load of the roll on the shaft from said jacks.

3. A winder machine adapted for producing a wound roll of a controlled uniform degree of hardness irrespective of the weight thereof, which comprises a pair of under winder drums defining a winding nip, upright tracks on said machine in parallel alignment and adjacent the ends of the winder drums, bearing means slidably supported in said tracks, fluid pressure actuated means engaging said bearing means for raising and lowering the bearing means in the tracks, a winder shaft extending along the length of said winding nip and having end portions rotatably supported in said bearing means, a shell enveloping said shaft between the supported ends thereof and receiving the wound roll of paper therearound, and deformable means supporting the shell in spaced concentric relation from the shaft at two localized points inwardly from the ends of the shell and shaft, whereby deflection of the shaft will be neutralized to maintain a substantial constant distribution of the load on the winder drum throughout the entire length of the roll.

4. A winder machine of the under drum type comprising a pair of under winder drums defining a winding nip, vertical tracks on said machine adjacent the ends of the winder drums, bearing supports slidably mounted in said tracks, fluid pressure actuated means engaging said supports for raising and lowering the supports in the tracks, a winder shaft extending along the length of said winding nip and having end portions rotatably mounted in said supports, a shell enveloping the winder shaft between the supports, and flexible supporting means between the shaft

and shell holding the shell in spaced concentric relation around the shaft and accommodating relative deflection of the shell and shaft, said supporting means being localized at two spaced areas each inwardly from the end of the shell and outwardly from the axial center of the shaft.

5. A winder machine adapted for producing a wound roll of a controlled uniform degree of hardness irrespective of the weight thereof, which comprises a pair of under winder drums defining a winding nip, upright parallel tracks on said machine adjacent the ends of the winder drums, a winder shaft extending along the length of said winding nip, bearings rotatably mounted on the end portions of the shaft and slidably retained in said tracks, fluid pressure actuated means engaging said bearings for raising and lowering the bearings in the tracks, a cylindrical shell on the shaft between the bearings, flexible supporting means connecting the shaft and shell, said means being disposed at two localized areas each inwardly from the ends of the shell and outwardly from the central portion of the shaft, and means for retaining said means in said areas, whereby deflection of the shaft between the bearings will not be imparted to the shell and the deflection of the shell under load will be neutralized between the portions of the shell beyond the supporting connecting means and the portion of the shell between the supporting connecting means.

6. A winder machine adapted for producing a wound roll of a controlled uniform degree of hardness irrespective of the weight thereof, which comprises a pair of under winder drums defining a winding nip, vertical tracks on said machine adjacent the ends of the winder drums, a tubular winder shaft extending along the length of said winding nip, stub shafts anchored in the ends of said tubular shaft and extending therefrom, bearings rotatably mounted on said stub shafts and having self-aligning arcuate portions, said bearings being slidably retained in said tracks, fluid pressure actuated means engaging said bearings for raising and lowering the bearings in the tracks, a shell enveloping the tubular shaft between the bearings, and resiliently deformable means supporting the shell in spaced concentric relation from the tubular shaft, said means including a pair of supports each spaced inwardly from the ends of the shell and outwardly from the axial central portion of the shaft.

7. A winder shaft comprising a through axle having solid end portions and a hollow central portion, said hollow central portion having reduced diameter areas near the ends thereof defining opposed shoulders, rubber rings disposed around said reduced diameter portions and abutted by said shoulders, a metal shell surrounding the hollow portion of the shaft and snugly engaging said rubber rings, and retainer rings in said shell abutting the innermost rubber rings, whereby said shell is supported on resiliently deformable rubber rings inwardly from the ends of the shell to accommodate relative deflection of the shell and shaft.

8. An anti-deflection winder shaft for under drum paper winders and the like which comprises a metal shell, a fixed collar on one end of the shell, an internally threaded collar on the other end of the shell, an externally threaded collar threaded into said internally threaded collar slidably on said other end of the shell, said other end of the shell having a peripheral groove therearound, a split collar anchored in

said groove and defining an abutment shoulder for the externally threaded collar, a pair of spacer sleeves bottomed on the opposed collars on the ends of the shell adapted to receive a winder tube therebetween, a through axle in said shell, rotatable bearings on the ends of the axle beyond the shell, and rubber mounting means supporting the shell in spaced concentric relation from the axle at two localized points each inwardly from the ends of the shell and outwardly from the central portion of the axle.

9. A paper winder comprising a pair of under winding drums defining a winding nip therebetween, vertically guided bearing supports at the ends of the winder drums aligned with the nip, a winder shaft carried by said bearing supports extending through the nip, said winder shaft having rotatable bearings on the ends thereof seated in said bearing supports, a cylindrical shell on the winder shaft between the bearing supports and extending along the length of the nip, rubber rings supporting the shell in spaced concentric relation from the shaft at two localized areas inwardly from the ends of the shell and outwardly from the longitudinal center of the shell, said shell having a peripheral groove around one end portion thereof, said shell hav-

ing a fixed abutment shoulder around the other end portion thereof, a removable retainer in said groove forming a second abutment shoulder, nested collars in threaded engagement bottomed on said second shoulder, spaced sleeves on the opposite ends of the shell respectively bottomed on the first shoulder and on the collar, said sleeves adapted to clamp a paper winding tube on the shell therebetween, and means for raising the bearing caps to lift the shaft for transferring part of the weight of the roll being wound off of the winder drums.

LLOYD HORNBOSTEL.
